CLAIM

The ornamental design for a food container as shown and
described.

DESCRIPTION

FIG. 1 is a top front perspective view of the food container,
according to the new design.

FIG. 2 is a bottom front perspective view of the food
container shown in FIG. 1.

FIG. 3 is a top front isometric perspective view of the food
container shown in FIG. 1.

FIG. 4 is a right side perspective of the food container shown
in FIG. 1.

FIG. 5 is a front elevation view of the food container shown
in FIG. 1.

FIG. 6 is a rear elevation view of the food container shown
in FIG. 1.

FIG. 7 is a left side elevation view of the food container
shown in FIG. 1.

FIG. 8 is a right side elevation view of the food container
shown in FIG. 1.

FIG. 9 is a top plan view of the food container shown in FIG.
1; and,

FIG. 10 is a bottom plan view of the food container shown
in FIG. 1.
